UNITED STATES PATENT OFFICE.

WILLIAM McCALLUM, OF SOUTH ORANGE, NEW JERSEY, ASSIGNOR TO THE
BIGELOW CARPET COMPANY, OF CLINTON, MASSACHUSETTS.

DESIGN FOR A CARPET.

SPECIFICATION forming part of Design No. 13,629, dated February 20, 1883.

Application filed January 17, 1883. Term of patent 3½ years.

To all whom it may concern:

Be it known that I, WILLIAM McCALLUM, of South Orange, in the county of Essex and State of New Jersey, have invented a new and 5 Original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design.

B is a flower group containing a central bunch of star-flowers, projecting from which is 15 an open flower, b, a flowering branch, c, and numerous leaves and branches. From one side of the group B projects the long stem D, which, after some distance, divides into two curving branches, the branch on the left connecting 20 with the flower group C, which consists of a center of open flowers from which in turn ex-

tend leaves, flowers, and leafy sprays, and this group C has projecting from it a leafy branch, g, and is also connected by the stem a with the flower group B. The figure E represents a 25 flower group composed of circular flowers in the center surrounded by leaves and foliage, and is connected by the stem d with the central flower group, B. The whole effect of the design is that of a plain background having 30 upon it the flower groups B, C, and E, which are apparently joined by the curving vine D, running through the pattern.

I claim—

The design for carpets, consisting of the 35 group B, containing figures b c, vine D, group C, figures g and a, group E, and figure d, substantially as shown.

WILLIAM McCALLUM.
